UNITED STATES PATENT OFFICE.

HARRY R. SINCLAIR, OF WORCESTER, MASSACHUSETTS.

CHECK-PROTECTOR.

1,143,556.

Specification of Letters Patent. Patented June 15, 1915.

Application filed February 27, 1915. Serial No. 10,944.

To all whom it may concern:

Be it known that I, HARRY R. SINCLAIR, a citizen of the United States, residing at Worcester, county of Worcester, State of Massachusetts, have invented an Improvement in Check-Protectors, of which the following description, in connection with the accompanying drawing, is a specification, like characters on the drawing representing like parts.

This invention relates to pocket check protectors both for perforating the check to indicate the face value thereof and for inking the perforations, and the object of the invention is to provide a novel pocket check protector of this type which can be inexpensively manufactured; which is light in weight and can be carried in the pocket without inconvenience; which is easy to operate, and which has other advantages, all as will be more fully hereinafter described.

In order to give an understanding of my invention I have illustrated in the drawings a selected embodiment thereof which will now be described, after which the novel features will be pointed out in the appended claims.

In the drawings, Figure 1 is a plan view of a check protector embodying my invention; Fig. 2 is a section on the line $x-x$, Fig. 1; Fig. 3 shows one of the puncturing caps before it is applied to the plate which carries it; Fig. 4 is an enlarged sectional view through one of the puncturing arms on the line $y-y$, Fig. 1; Fig. 5 is a view of the bottom plate removed.

In designing my present invention I have aimed to provide an inking check protector which is greatly simplified in construction in that it is composed of a minimum number of parts and which can be readily taken apart to permit the inking pad to be freshly inked. The device herein shown comprises a bottom plate 1 preferably made of sheet metal which will be stamped or pressed into shape to form on its exterior edge an annular lip 2 and will be formed centrally with the upturned annular flange 3 having at its upper edge the curved portion 4. This bottom plate 1 sustains an annular inking pad 5 which is held in place thereon by the upturned lip 2. Situated above the inking pad 5 is a protecting plate 6 having therein a plurality of sets of perforations 8 formed to indicate the characters it is desired to

perforate in the check, these preferably being the ten digits and a dollar mark.

Situated above the protecting plate 6 is a puncturing member in the form of a resilient circular plate 7 which is secured to the plate 6 and which is provided with a plurality of radial arms 9, each of which carries at its end a set of puncturing points 10, these puncturing points being situated directly over the apertures 8, so that the depression of any arm 9 will force the puncturing points thereon through the apertures 8. To provide a simple way of securing the plates 6 and 7 together I propose to form the plate 6 with the annular upturned portion 11 and with the horizontal portion 12 which constitutes a rest or support for the central portion of the plate 7, the latter being formed with a central aperture, and the plate 6 being formed with the portion 13 which extends through the aperture and is bent over on the top of the plate 7 thereby rigidly securing the plate 7 onto the rest portion 12 of the plate 6. The bottom plate 1 is secured to the plates 6 and 7 by the curved annular portion 4 of the bottom plate which engages the portion 13 of the plate 6, as shown in Fig. 2. The upturned portion 3, 4 of the bottom plate is preferably slotted at one or more points, as shown at 20, so that it will be sufficiently resilient to permit it to be snapped into or snapped out of the portion 13 of the plate 6, thus providing for a detachable connection between these parts. The purpose of this is to permit the ready inking of the pad 5, for when the pad needs to be inked the bottom plate 1 can be snapped off from the combined plate 6 and 7, thus exposing the inking pad for the reception of ink. After the pad has 95 been inked the parts can be snapped together again, as will be obvious.

The puncturing points 10 are formed on heads or caps 14 which are applied to the ends of the arms 9. These caps are first formed with a cup shape shown in Fig. 3 and with the puncturing points 10 on the under face thereof, one side of the cup portion being cut out, as shown at 15. The cap is then applied to the rounded end 16 of the arm 9 and the upper edge 21 of the cup is upset or bent over onto the peripheral edge of the head 16, as shown in Fig. 4, thus rigidly securing the cap to the head. One advantage of this construction is that this 110

clenching or upsetting process forms a bead or rim 21 around the edge of the cap which serves as a means for holding the operator's finger in position on the end of the arm 5 while pressure is being applied to the arm for puncturing a check. The puncturing points 10 will preferably be made in the form of self-stripping points so that they will strip themselves from the punctured 10 paper without the necessity of employing a stripper plate for this purpose. This can be accomplished by making the points comparatively stubby, as shown.

I claim:

15 1. In a check protector, the combination with a bottom plate, of an inking pad sustained thereon, a protective plate overlying the inking pad and formed of a plurality of apertures representing characters, a perforating plate secured to the protective plate and provided with a plurality of resilient arms, each carrying puncturing points representing a character, said latter plates hav-

ing a central aperture and the bottom plate having a yielding boss to enter said aperture and detachably engaging the periphery thereof whereby said bottom plate is detachably connected to the other plates. 25

2. In a check protector, the combination with a plate provided with perforations representing characters, of a perforating plate presenting a plurality of resilient arms, a puncturing cap applied to the end of each arm and having a bottom portion that underlies the bottom face of the arm and is 30 provided with puncturing points, and side walls that embrace the edge of the arm and overlie the periphery thereof thereby forming a finger-guiding bead. 35

In testimony whereof, I have signed my 40 name to this specification, in the presence of two subscribing witnesses.

HARRY R. SINCLAIR.
